(57) **CLAIM**

The ornamental design for a door lock, as shown and described.

DESCRIPTION

FIG. 1 is a top, front and right side perspective view of a door lock showing my new design;

FIG. 2 is a front elevational view thereof;

FIG. 3 is a right side elevational view thereof;

FIG. 4 is a slightly enlarged top plan view thereof, the bottom plan view being a mirror image of that shown;

FIG. 5 is slightly enlarged rear elevational view thereof; and,

FIG. 6 is a slightly enlarged left side elevational view thereof.
